US00D930624S

(12) **United States Design Patent** (10) **Patent No.:** **US D930,624 S**
(45) **Date of Patent:** **** Sep. 14, 2021**

(54) **MICROPHONE**

(71) Applicant: **Logitech Europe S.A.**, Lausanne (CH)

(72) Inventor: **James Edward Renwick**, Portland, OR (US)

(73) Assignee: **LOGITECH EUROPE S.A.**, Lausanne (CH)

(**) Term: **15 Years**

(21) Appl. No.: **29/707,728**

(22) Filed: **Sep. 30, 2019**

(51) LOC (13) Cl. **14-01**

(52) U.S. Cl.

USPC **D14/227**

(57) **CLAIM**

The ornamental design for a microphone, as shown and described.

DESCRIPTION

FIG. 1 is a top front left side perspective view of a microphone according to our design;

FIG. 2 is a top rear right side perspective view of the microphone shown in FIG. 1;

FIG. 3 is a bottom front left side perspective view of the microphone shown in FIG. 1;

FIG. 4 is a bottom rear right side perspective view of the microphone shown in FIG. 1;

FIG. 5 is a front view of the microphone shown in FIG. 1;

FIG. 6 is a right side view of the microphone shown in FIG. 1;

FIG. 7 is a rear view of the microphone shown in FIG. 1;

FIG. 8 is a left side view of the microphone shown in FIG. 1;

FIG. 9 is a top view of the microphone shown in FIG. 1; and, FIG. 10 is a bottom view of the microphone shown in FIG. 1.

The broken lines shown in the drawings depict portions of the microphone assembly that apparatus form no part of the claimed design.

1 Claim, 9 Drawing Sheets
